(57) **CLAIM**

The ornamental design for a molding structure of electric element, as shown and described herein.

DESCRIPTION

FIG. 1 is a perspective view of a molding structure of electric element;

FIG. 2 is a right side elevational view thereof;

FIG. 3 is a top plane view thereof;

FIG. 4 is a front elevational view thereof;

FIG. 5 is a bottom plane view thereof;

FIG. 6 is a left side elevational view thereof; and,

FIG. 7 is a rear elevational view thereof.
